UNITED STATES PATENT OFFICE

2,564,261

STRAIGHT BAR KNITTING MACHINE

Gustav Huber, Cleator, England, assignor to
 Kangol Patents Limited, London, England, a
 British company

Application February 27, 1950, Serial No. 146,561
 In Great Britain March 1, 1949

3 Claims. (Cl. 66—76)

1

This invention relates to improvements in straight bar knitting machines such as are used for the production of a knitted fabric applicable for the manufacture of berets and other shaped articles.

In such machines the selection of the needles required to be operated at each transverse of the cam box or cam carriage, which acts on the needles for the formation of the stitch, is controlled by a cylinder which carries on its peripheral surface a series of projecting strips arranged parallel to the axis of the cylinder. The cylinder is rotated about its axis through a given angular distance after each traverse of the cam box or carriage and is mounted so that it has a reciprocating movement or an oscillating movement about a centre at some distance from the cylinder, whereby a strip thereon will engage the rear of the needles which it is desired to be selected to be operated on by the cam or carriage. The strips secured to the surface of the cylinder may vary in length so that they will select the number of needles required for the particular portion of the fabric being knitted thereby controlling the necessary decreases and increases in the width of the fabric.

The number of longitudinal strips which can be arranged around the periphery of the cylinder is limited and hence the number of changes in the selection of the needles is also limited and the object of the present invention is an arrangement in substitution for the usual cylinder of means which will allow a very large number of changes in the selection of the needles.

This object is achieved according to the present invention by carrying each of the needle selection strips on a longitudinal member secured at each end to a chain or equivalent device passing over a sprocket or similar wheel affixed on a shaft which is given an intermittent rotary movement and a reciprocating or oscillating movement to bring each selection strip successively into engagement with the ends of the needles.

The chains or equivalent devices carrying the longitudinal members can be of any required length so that any desired number of selection strips can be employed since the portions of the chains or equivalent devices not in engagement with the sprocket or similar wheels will depend downwards from the wheels.

The invention is illustrated in and will be described with reference to the accompanying drawings in which:

Fig. 1 is a front elevation of a portion of the chains and longitudinal members showing them passing round the sprocket wheel;

2

Fig. 2 is an end view of Fig. 1;

Fig. 3 is a plan view, drawn to a larger scale, of two longitudinal members and their connecting links;

5 Fig. 4 is a section on line 4—4 of Fig. 3;

Fig. 5 is an elevation of a longitudinal member showing means for affixing a needle selecting strip thereto; and

Fig. 6 is a section on line 5—5 of Fig. 5.

10 10 Each needle selecting strip A is secured to a longitudinal member B which at each end is attached to or formed integrally with a link C of a chain passing around a sprocket wheel D affixed on a shaft D¹. The shaft D¹ is intermittently rotated and is given a reciprocating movement or an oscillating movement about a centre at some distance from the shaft D¹ to bring each strip A successively into contact with the rear of the needles which it is desired to be selected to be operated on by the cam box or carriage of the knitting machine.

The needle selecting strip A may be secured to the longitudinal member B in any suitable way and the longitudinal members B may be of any desired construction. A form of longitudinal member B which is at present preferred and the method of securing the needle selecting strip A thereto is shown in the drawings but it is to be understood that this form is only illustrative of the invention.

30 30 The longitudinal member B consists of two stiff wires or rods of small diameter b formed at each end with a link C. Each link C is separable from the next link and is readily attachable thereto so that the longitudinal member B and the link C at each end thereof constitute a complete unit.

The needle selecting strip A is of T shape in cross section and is secured to the wires or rods b or the member B by a series of pair of clamping plates a which have curved ends to encircle partly the wires or rods b. The clamping plates of each pair are clamped together with the perpendicular flange of the strip A between them by means of the screws or bolts a¹. If necessary to prevent distortion of the wires or rods b by the clamping

40 40 plates, a distance piece b¹ (see Fig. 6) may be arranged between them where each pair of clamping plates is located.

45 45 The needle selecting strips A may consist of an aluminium or other light weight alloy with a steel plate to form the face which engages the ends of the needles.

When the pattern or shape of the fabric requires the end needle or needles to operate as a half-needle or tuck stitch needle, the end or ends 50 50 of the selecting strip are stepped so that the

needle or needles engaged by the stepped portion will only be moved half their normal distance.

Spring means acting on the end of the shaft ^{D¹} carrying the sprocket wheels D may be provided to ensure that after each rotary movement of the shaft it will be stopped in the correct position to ensure that the selecting strip A which is to engage the needles in the next forward movement of the shaft, will be perpendicular to the ends of the needles when brought into contact ¹⁰ therewith.

Any number of longitudinal members B each carrying a needle selecting strip A can be employed in the form of an endless band and to remove one such band and replace it by another it is only necessary to uncouple a pair of adjacent links of each end chain. Thus when it is desired to change the shape or pattern of the fabric being knitted the time necessary for change is short.

Moreover if it is desired to replace one or more of the longitudinal members B it is only necessary to uncouple the members it is desired to replace and substitute other members therefor.

The needle selecting strips A are easily replaceable on the longitudinal members B as it is only necessary to loosen the clamping screws or bolts ^{a¹} to enable a strip to be removed and replaced by another strip.

I claim:

1. Patterning mechanism having a plurality of needle selecting strips for a straight bar knitting machine for the production of a knitted fabric applicable for the manufacture of berets and other shaped articles comprising the combination with each needle selecting strip of a longitudinal member to which the selecting strip is secured, means at each end of the longitudinal member for attaching the members together to form an endless band at each end of the member, an intermittently rotated shaft having a to and fro ³⁰ ³⁵ movement and a pair of driving wheels, one for each band, secured on said shaft and spaced part at a distance equivalent to the length of the longitudinal member.

2. Patterning mechanism having a plurality of needle selecting strips for a straight bar knitting machine for the production of a knitted fabric applicable for the manufacture of berets and other shaped articles comprising the combination with each needle selecting strip of a pair of longitudinal rods to which the selecting strip is detachably secured, a link at each end of the longitudinal rods, the links at each of the ends of the plurality of pairs of rods being adapted to be attached together to form an endless chain, an intermittently rotated shaft having a to and fro movement, a pair of sprocket wheels, one for each chain, secured on said shaft and spaced apart at a distance equivalent to the distance between the two links at the ends of each pair of rods to which the selecting strips are secured.

3. In patterning mechanism for a straight bar knitting machine as in claim 2 the combination with each pair of longitudinal rods to which a needle selecting strip is secured of a plurality of pairs of clamping plates adapted to clamp the selecting strip to the rods and screwed means for tightening each pair of plates on to the strip and the rods.
